Patented Mar. 16, 1915.

UNITED STATES PATENT OFFICE.

GEORGE B. KELLY, OF JAMAICA PLAIN, MASSACHUSETTS, ASSIGNOR TO AEOLIAN COMPANY, OF NEW YORK, N. Y., A CORPORATION OF CONNECTICUT.

COMBINED PIANO-PLAYER AND TALKING-MACHINE.

1,132,275.

Specification of Letters Patent.

Patented Mar. 16, 1915.

Application filed December 6, 1912, Serial No. 735,195. Renewed February 8, 1915. Serial No. 6,822.

To all whom it may concern:

Be it known that I, GEORGE B. KELLY, a citizen of the United States, and resident of Jamaica Plain, in the county of Suffolk and State of Massachusetts, have invented certain new and useful Improvements in Combined Piano-Players and Talking-Machines, of which the following is a specification.

The object of my invention is to provide a new and improved combined player piano and talking machine, which is simple in construction, reliable in action, and easily adjusted to maintain substantial synchronization of the talking machine record and the perforated music sheet of the player piano.

In the accompanying drawing I have shown the front elevation of the upper part of a player piano combined with a talking machine according to my present invention.

The tracker 1, the music roll 2, and the take-up roll 3, for the perforated music sheet 4 are mounted in the conventional manner between the side walls 5 of a chest 6 and the said rolls are rotated in the conventional manner by means of a motor 16, preferably an air motor of any approved construction, the motor *per se* forming no part of the present invention. The speed of the motor is controlled by a tempo lever 7 in any well known manner.

The rotating support 8 for a talking machine disk or record 9 is mounted on the upper end of a shaft 10 which is driven by means of a spring motor 11, such as commonly used in a Victor talking machine and is well known. By means of the beveled gearing 12 a horizontal shaft 13 is rotated, which shaft is mounted in the end walls 5 of the chest 6 and carries a disk 14 adjacent to one side wall 5 of the chest, preferably the right hand side wall. This disk 14 will thus have the same proportionate speed as the record 9 on the support 8 and this disk 14 is provided on its rim with a number of equi-distant indicia 15. There may be only one of such indicia representing a full rotation of the disk 14 or there may be two of such indicia indicating half rotations or four indicia indicating quarter rotations, and so forth as may be desired. These subdivisions or indicators are each marked 1, 2, 3, etc., respectively, so that these indicia can readily be followed by the eye as the disk 14 rotates. A pointer 17 projects from the right hand wall 5 of the chest 6 over the rim

of the disk 14 so that as the disk rotates the indicia 15 pass said pointer. The music sheet 4 is provided along one edge, in this case, the right hand edge, with a series of equally spaced indicia α which are marked to correspond with the indicia on the rim of the disk 14. For example, if the rim of the disk 14 is divided into four parts the indicia α on the sheet are marked 1, 2, 3, 4, then the next indicia 1, 2, 3, 4, and so on. Each subdivision or one of said indicia thus produced on the music sheet corresponds to one subdivision on the disk 14. In making the music sheet master one such mark α of the music sheet is produced regularly on the moving master sheet for each fraction of a complete rotation of the record disk 9. If the disk 14 has but a single mark on its rim the indicia α on the edge of the music sheet will be separated from each other a distance corresponding to one full rotation of the disk 14, or which is the same, one complete rotation of the record disk 9. A pointer 18 projects from the right hand side wall 5 of the chest to the right hand edge of the music sheet or may slightly overlap the same. The speed of rotation of the record disk 9 is uniform throughout, as in all talking machines, and if the speed of the music sheet is so adjusted that its sub-division marks or indicia α appear at the pointer or marker 18 at the same instant that the corresponding sub-division indicia on the disk 14 appear at the pointer 17 the disk and the music sheet will be synchronized. If it should appear that the music sheet moves too slowly or too rapidly to obtain exact synchronizing it is only necessary to manually move the tempo lever 7 correspondingly to one side or the other sufficiently to slightly increase or decrease the speed of the motor and thereby the speed of the music sheet, so as to cause the corresponding indicia on the disk 14 and music sheet to register with their respective pointers at precisely the same time.

Having described my invention what I claim as new and desire to secure by Letters Patent is:—

1. The combination with a player piano comprising a motor for moving a perforated music sheet, a manual means for controlling the speed of said motor and a talking machine comprising a movable support, a motor therefor independent of the sheet moving motor, of a movable element driven by

- the record moving motor at a speed proportionate to the speed of the record support and provided with permanent visible indicia, a pointer adjacent to said movable element, a perforated music sheet driven by said sheet moving motor and provided with indicia, separated a distance to be traversed by the music sheet during one rotation of the record disk support and a fixed pointer adjacent to said sheet, the indicia on the movable element being so positioned and so driven that a mark comes opposite the adjacent pointer for each rotation of the record support, whereby an observation of the two pointers and of the arrival of the indicia on the element driven from the talking machine motor and on the music sheet, at said pointers, indicates any existing variation in relation to the speed of the driven elements and permits of rectifying such variation by means of the manual speed control for the music sheet motor, substantially as set forth.
2. The combination with a player piano comprising a chest, a perforated music sheet on one of said rolls, music rolls in said chest and a motor for moving the perforated music sheet connected with said rolls and a talking machine comprising a motor for rotating a record independent of the sheet moving motor, a disk mounted within said chest and driven from the talking machine record motor at a speed proportionate to the speed of the record, indicia on the rim of said disk, said music sheet having indicia permanently produced thereon, said indicia being spaced at a length of the music sheet, which is to be traversed by the sheet during one rotation of the record support, in order to obtain synchronism, and fixed pointers extending to the said disk and to the said music sheet, the indicia on the movable elements being so positioned and

driven that a mark comes opposite the adjacent pointer for each rotation of the support, when the disk and sheet are moving synchronously, substantially as set forth.

3. The combination with a player piano comprising a chest, music rolls in said chest, a perforated music sheet on one of said rolls, a motor for moving said perforated music sheet, connected with said rolls and a talking machine comprising a motor for rotating a talking machine record support independent of the perforated sheet moving motor, a movable element driven from the talking machine record motor at a speed proportionate to the speed of the record support, said element being located within said chest, equally spaced indicia on said element driven from the talking machine record motor, indicia permanently produced on the perforated music sheet, said indicia on the perforated music sheet being spaced at a length of the music sheet which is to be traveled by said sheet during a predetermined part of a rotation of the record support, the moving element driven from the talking machine motor and provided with indicia as aforesaid, being adjacent to that part of the perforated music sheet which carries the indicia on said sheet, whereby the indicia on the perforated music sheet and the indicia on the element driven from the motor of the talking machine record are simultaneously visible, and means for controlling the speed of the motor for moving the perforated music sheet, substantially as set forth.

Signed at New York city, in the county of 80 New York and State of New York this 1st day of December A. D. 1912.

GEORGE B. KELLY.
